DESIGN FOR A ROSARY BEAD

Horace Randall, Pawtucket, R. I., assignor to
H. M. H. Company, Pawtucket, R. I.

Application June 6, 1941, Serial No. 101,331

Term of patent 14 years

To all whom it may concern:

Be it known that I, Horace Randall, a citizen of the United States of America, residing at Pawtucket, in the county of Providence and State of Rhode Island, have invented a new, original, and ornamental Design for Rosary Bead, of which the following is a specification, reference being had to the accompanying drawing, forming part thereof.

In the drawing:

Figure 1 is a top plan view of a rosary bead showing my new design;

Figure 2 is a side elevational view thereof; and

Figure 3 is an end elevational view of the bead.

I claim:

The ornamental design for a rosary bead, as shown.

HORACE RANDALL.
